ELECTRICAL CONTROL EQUIPMENT

Charles R. Hodgson, Atlanta, Ga., and Harry H. Knowles, Birmingham, and George N. Lemmon, Homewood, Ala.

Application December 8, 1932, Serial No. 646,278

4 Claims. (Cl. 200—97)

The purpose of our invention is to provide a means to open or close a circuit at will with no delay, and to open the circuit automatically in case the power supply ceases for a predetermined time interval, but to keep the circuit closed if the power supply ceases momentarily but comes back before the predetermined time interval has elapsed.

Referring to the drawing, Fig. 1 shows in small scale one of the devices in its box; Fig. 2 shows in larger scale the general appearance of the mechanism with the box removed; Fig. 3 is a similar view of some of the working parts in different positions than shown in Fig. 2. Fig. 4 is a partial cross-section through the cover on the line AA; and Fig. 5 is a diagram of the electrical connections for one method of using the device.

The mechanism includes a box 1, with a cover 2 in which are mounted two push-buttons 3 and 4. Wires enter the box through the conduit 5.

Inside the box is a removable base plate 6 upon which a revolvable induction disc 7 is mounted, one bearing being in the base 6 and one in the extended arm 8. The induction disc 7 passes between the terminals of the electromagnet 9, where the alternating current in the coil 10 creates an A. C. magnetic field, causing the disc 7 to tend to revolve as shown by the arrow. This is the well-known induction disc action such as is often used in electric meters. The bearing 8' and the corresponding bearing in the plate 6 receive the ends of the pinion shaft which is the center of 7. The teeth on this pinion are engaged by the teeth of the movable plate 11, which is pivotally connected by the links 12, 12' to the rocker-arm 13. A compressed spring 14 biases the arms 12, 12' and the plate 11 towards the extended position, and stops limit their range of travel. The rocker-arm 13 is movable about the pivot 15, and it carries the mercury switch 16, which is held to the arm by suitable clips. The switch has two projections 17 where the terminals are located, and the circuit through the switch is opened or closed as the bath of mercury 18 is rocked back and forth by motion of the arm 13. Leads as shown connect the terminals to the block 19.

Pivoted to 8 is the member 20, 21, 22, which is limited in its travel by the arm 21 and suitable stops. The face 20 is operable to press against 11 and disengage the teeth of 11 from the pinion of 7, while leaving 11, 12 and 13 free to be raised or lowered, as 11 slides easily over the face 20. The arm 22 is engageable by arm 23 which is mounted on the pivot 25 inside the cover 2, as shown in Fig. 4.

The parts 3, 4, 23 and 24 are all attached to the cover 2, and are included in Fig. 2 in order to show their relative positions. When the button 4 is pushed inwardly against the arm 24, it rotates 25 and also 23, thereby moving 22 so that 20 pushes 5 11 away from the pinion shaft of 7 and 13 drops by gravity until stopped by the pin 34, as shown in Fig. 3. The various parts are so proportioned that, if the teeth on 11 are engaged with the pinion of 7, the mercury closes the switch-contacts 10 17; and if 11 is below the position of engagement with the pinion of 7, then the mercury-switch is open.

Secured to the plate 6 is an extended arm 26 at the outer end of which is a pivot shaft carrying 15 the arms 27 and 28. The arm 27 is engaged by the button 3 and rotates the arm 28 which extends inwardly and engages with the arm 29 on 13. When the button 3 is pushed in 27 and 28 rotate, 28 engages with 29 and lifts 13 up from its 20 position in Fig. 3 until the upper teeth on 11 engage with the teeth on the pinion of 7. When the teeth touch, further motion of 13 causes the spring 14 to be compressed as the links 12, 12' rock 25 around their pivots, thereby bringing 11 closer to 13 and allowing the teeth on 11 to slip past those on the pinion. In effect, the member 11 acts like a ratchet with many teeth.

When the pressure on 3 and 13 is released, 11 is extended into proper engagement with the pinion, where it is held by the spring 14 and the stop as shown in Fig. 2.

Meanwhile the mercury switch has closed its contacts and, as shown in Fig. 5, this bridge current from the incoming lines 30, 31 to the coil 10. 35 Thereupon, following well-known principles, the induction disc 7 begins to revolve, and so the teeth on the pinion lift the member 11 upwards until it reaches the limit of its travel. This limit can be varied by moving the adjusting screw 32 up or 40 down. Since the mercury-switch maintains closed contact over a considerable range of motion, there is quite a wide range of adjustment possible without opening the mercury-switch contacts. 45

So long as power is maintained on the line 30, 31, the electromagnet will keep a slight torque on 7 and the switch will remain closed. Whenever power goes off the line, 10 releases its torque on 7, which then revolves backwards under the weight 50 of 13 and its associated parts. If power stays off, 11 lowers until all its teeth disengage from the pinion, whereupon the mercury switch drops to the fully open position and remains open until manually reclosed, for the mercury switch opens 55

the circuit of the coil 10 as well as that of the motor 35.

If power goes off the line momentarily, and comes back soon enough, the disc 7 will start to 5 revolve backwards and lower the arm 13, but when power comes back the coil 10 will again be energized and so revolve 7 forwards until 13 is again brought against the stop 32.

Whenever it is desired to open the circuit manually, the button 4 is pushed in. This pushes the 10 face 20 against 11, disengaging it from the pinion teeth, whereupon 11, 13, 16 and their associated parts all drop to the open position as shown in Fig. 3.

15 The distance which the rack has to drop down before it becomes disengaged from the pinion of 7, varies the time interval between the instant power goes off the line and the time the circuit is opened by the mercury-switch. The adjustment 20 screw 32 thus provides a means to alter this time interval as desired. If a still longer interval is required, a fixed magnet 33 is placed so that the disc revolves between its poles and so is retarded in its turning.

25 There are many variations which can be made. Instead of using the weight of the mercury switch to open the circuit when power goes off the line, the mercury switch can be held in a stationary position by a latch which is released by 30 another weight which is similarly lowered by the reverse motion of the disc. Other variations can also be made without departing from the fundamental idea of this invention.

We claim:

1. Electrical control equipment which comprises an electromagnet operating an induction disc which is connected by gearing to a mercury-switch, together with means to disconnect the gearing if the electro-magnet becomes de-energized for longer than a predetermined time.

2. Electrical control equipment which comprises an electromagnet operating an induction disc which is connected by gearing to a mercury-switch, and means to disconnect the gearing if the electromagnet becomes de-energized for longer than a predetermined time, together with means to disconnect or reconnect the gearing at will.

3. Electrical control equipment which comprises a mercury-switch, an electromagnet operating an induction disc, and control means operable by the induction disc to operate the mercury-switch once only if the electromagnet becomes de-energized for longer than a predetermined time.

4. Electrical control equipment which comprises a mercury-switch, an electro-magnet operating an induction disc, and control means operable by the induction disc to operate the mercury-switch if the electromagnet becomes de-energized for longer than a predetermined time, together with means to operate the mercury-switch without movement of the induction disc.
